(57) **CLAIM**

The ornamental design for a medical drainage tube anchor, as shown and described.

DESCRIPTION

FIG. 1 is a front, right side perspective view of the medical drainage tube anchor showing the new design; FIG. 2 is a rear, right side perspective view thereof; FIG. 3 is a front perspective view thereof; FIG. 4 is a rear elevation view thereof; FIG. 5 is a front, right side perspective view thereof; FIG. 6 is a rear, left side elevation view thereof; FIG. 7 is a top plan view thereof; FIG. 8 is a left side elevation view thereof; FIG. 9 is a front, left-side perspective view thereof; FIG. 10 is a right side elevation view thereof; FIG. 11 is a front elevation view thereof; FIG. 12 is a bottom plan view thereof; FIG. 13 is an illustrative left side elevation view showing the anchor while attached to the rim of a waste receptacle; FIG. 14 is an illustrative top perspective view showing the anchor attaching a drainage tube to a waste receptacle; and, FIG. 15 is an illustrative top perspective view showing the anchor attaching a drainage tube to a waste receptacle. The broken lines shown in the drawings represent environmental matter and form no part of the claimed design.
